GUARD FOR ROLLER WINDOW SHADES

Filed July 5, 1924

Inventor
Wm B Boyce
by Clark & Mahan Law Atty.

UNITED STATES PATENT OFFICE

WIRT B. BOYCE, OF CHICAGO, ILLINOIS

GUARD FOR ROLLER WINDOW SHADES

Application filed July 5, 1924. Serial No. 724,188.

My invention relates to the shading of windows in which the control of air for ventilation is provided by a plurality of sashes of the guillotine type in adjacent ganes or channels. In windows of this class movement of the upper sash permits currents of air to pass at the upper part of the window casing; by raising the lower sash, currents pass at the lower portion of the casing; while by slight movement of either or both of said sashes, valuable additional ventilating currents are created between the top and bottom, passing between the adjacent horizontal rails of the two sashes. It is well known that the action of the ordinary single spring roller curtain, when the roller is mounted either at the top or bottom of the window frame, is seriously interfered with and rapidly destroyed by the currents of air passing through the windows when open or partly open for ventilation. Great advantage has been derived by mounting a plurality of spring shade rollers on the casings between the top and bottom thereof in such a manner that there is no substantial loss of light, at the point of mounting, against sudden and violent currents of air.

It is one object of my invention to provide an improved rigid and opaque light and air guard for centrally mounted shade roller curtains, and further to provide brackets adapted to support the ends of said guards and the ends of the shade roller bearing supports so as to position said guards and the curtain rollers in proper relation to each other. It is a further object to secure the guard positively in place and yet provide means by which it may be readily removed and replaced, and in which the relatively adjustable parts may be easily made from the chosen materials and readily formed into the desired shape and assembled without difficulty.

The principles of my invention are illustrated in the drawings, in which Fig. 1 is an adjustable and extendable light shade; Fig. 2 is an end view thereof looked at from the left; Fig. 3 represents strengthening and supporting pieces for the ends of said light shade; Figs. 4 and 5 are respectively left

and right hand suspending brackets in their substantially normal relation to the shield piece; Fig. 6 is one of a similar pair of brackets adapted to attachment with the inner finishing pieces of the window casing.

Further describing my invention with reference to the drawings in which like characters of reference denote like parts throughout: Numeral 1 is one of the sliding sheet metal members of my improved light guard; the side edges 2 are turned forwardly and inwardly to provide stiffening ribs 3. A transverse stay piece, as shown in Fig. 3, having the body portion 4 and suspending tenon member 5 is attached to the end of member 1 by riveting or, preferably, by spot welding. A second relatively sliding member 1' having corresponding edges 2' is formed from sheet metal in such a manner that said edges turn over and embrace the corresponding edges of member 1. Said member 1' is also provided with a transverse stay piece, substantially as shown in Fig. 3, and secured thereto in the same manner as described with reference to member 1. The two members slide together as illustrated in Fig. 1 and the end 6 of member 1 will be received against edge 7 of the body 4 of the stay piece which forms a stop therefor. When thus assembled, the device is at its minimum length. In practice the two parts should be of such relative length that an overlap of several inches will not affect the rigidity of the structure and that the whole will be in completely rigid relation when mounted as hereinafter described.

The supporting brackets, shown in Figs. 4 and 5, are made in pairs, with the respective parts in reversed relation to each other, and comprise body portions 8 having elongated openings or sockets 9 of such shape and in such proportion as to correspond with the suspending projections or tenon members 5 of the light guard. The body portions are provided with bifurcations which, at their respective ends, have bearing openings 10 and squared retaining openings 11. Said bearing and retaining openings are in such relation to each other that they will respectively receive the stub shaft

at one end of an ordinary shade roller and the squared or flattened end of the spring shaft. The said brackets are provided with counter sunk openings 12 adapted to take screws by which they are secured in proper relation to the inside pieces of a window casing. When so secured in position, the suspending tenons 5 on the stay pieces are placed in proper relation to the sockets 9 and by extension the light strip is rigidly and securely placed and fastened in its normal position therein. It will be noted, however, that while the drawings show the light strip with the concave side toward the observer and looking into the room, it may be mounted in the other way with the smooth surface 13 next to the curtains and to the room and with the concave side towards the window sash. Fig. 6 is a bracket in all respects similar to the left hand bracket shown in Fig. 4, except that retaining lugs 14 are provided by which the bracket may be secured, if desired, to the outward finishing pieces of the window casing.

I claim:

- 25 1. In a guard for roller window shades; a shield piece of sheet metal comprising a plurality of members each having down-turned stiffening ribs on their corresponding side edges whereby said members are mutually and slidably engageable, and transverse stiffening pieces rigidly attached to the non-adjacent ends of said pieces, each of said pieces having a body portion and a suspending tenon.
- 30 2. In a guard for roller window shades; a shield piece of sheet metal comprising a plurality of members each having down-turned stiffening ribs on their corresponding edges, whereby said members are mutually and slidably engageable, transverse stay pieces extending across the non-adjacent ends of said members and rigidly secured thereto, and rigidly attached suspending tenons on said stay pieces.
- 35 3. In a light guard for roller window shades, a shield piece of sheet metal comprising a plurality of relatively short members each having down-turned stiffening ribs on its corresponding side edges whereby said members are mutually and slidably engageable, stay pieces on the ends of said members extending transversely thereof, and provided with rigidly attached tenons extendable with the stiffening members on substantially the center line of said light guard.

In witness whereof I have hereunto set my hand at Chicago, Cook County, Illinois, 60 this 2nd day of July, 1924.

WIRT B. BOYCE.
